UNITED STATES PATENT OFFICE

169,452

TOY BIRD FIGURE

Adam T. Norwich, Cleveland, Ohio

Application March 2, 1953, Serial No. 23,843

Term of patent 14 years

(Cl. D34—2)

To all whom it may concern:

Be it known that I, Adam T. Norwich, a citizen of the United States, residing in the city of Cleveland, county of Cuyahoga and State of Ohio, have invented a new, original, and ornamental Design for a Toy Bird Figure, of which the following is a specification, reference being had to the accompanying drawing, forming a part thereof:

Figure 1 is a front view of the toy bird figure, embodying my new design;

Figure 2 is a rear view thereof;

Figure 3 is a side view thereof; and

Figure 4 is a top view taken in the direction of the arrows 4—4 of Figure 3.

I claim:

The ornamental design for a toy bird figure, substantially as shown.

ADAM T. NORWICH.
